INVENTOR

BY *Willis Fowler*
ATTORNEY

UNITED STATES PATENT OFFICE.

CARL MACK, OF NEW YORK, N. Y., ASSIGNOR, BY MESNE ASSIGNMENTS, TO MACK
LOCK CO. INC.

LOCK KEEPER.

Application filed October 18, 1920. Serial No. 417,856.

This invention relates to a noiseless door lock keeper used particularly in automobiles, trucks, and other vehicle doors.

- Also it is of the greatest advantage to the above mentioned trades. Provisions are made for its use on ocean steamers, launches, motor boats, yachts, houses or wherever a keeper with absolute locking qualities is required.
- 10 One of the objects of this invention is to produce a keeper for the doors set forth, which has two or more locking chambers, whereby a twisted door is immediately brought into alignment.
- 15 A further object is to eliminate the rubber or spring bumpers, used at present to take up the play, required between the keeper on the post and the bolt of the lock in all locks used at present.
- 20 Another object is that the keeper which is attached to the post entirely surrounds the bolts of the lock, simultaneously preventing vertical, horizontal and traverse motion, thereby preventing any rattling, which can not be achieved by the methods used at present.

Still another object is that the keeper consists of several compartments with removable keeper blocks made preferably of fibre or other suitable soundless material. If the locking blocks wear out they can be replaced instantly without any fitting, bringing the door in the same alignment it had when new.

A still further object is, the alignment block in the centre compartment which is also removable; with this block the alignment of the pillar rabbet line may be continued.

Other objects and advantages will become apparent as the specification proceeds.

With the aforesaid objects in view the invention consists of the improvements, novel construction, arrangements and combinations of parts hereinafter described, defined in the subjoined claims and illustrated in the preferred embodiments by the annexed drawings, wherein like elements are designated by the same reference characters throughout.

In the said drawings:

Figure 1 is a front view of the keeper attached to the pillar. In the upper section the removable silencing block is inserted. In the lower half the block is removed.

Figure 2 is a side elevation of the keeper

attached to the pillar with upper silencing block attached, the lower removed.

Figure 3 is a front elevation of the keeper housing with all compartments vacant.

Figure 4 is a side elevation of the above mentioned keeper housing.

Figure 5 is a side elevation, front elevation and top plan view respectively of the alignment member 12.

Figure 6 is a section of the pillar before the keeper is attached.

Figure 7 is a section of the pillar with keeper attached to the same.

Figure 8 is a top plan view of the keeper with the alignment block extending to the extreme front edge of the keeper.

Figure 9 is a front view of the removable silence block and a section on line A—A, respectively.

Figure 10 is a section of the pillar, the space for the keeper frame cut away.

Figure 11 is a section of the pillar with keeper attached but without rabbet alignment block.

Figure 12 is a section of the pillar with keeper and rabbet alignment block in position.

Figure 13 is a front elevation of the pillar with the keeper, without rabbet alignment block.

Figure 14 is a front elevation of the pillar with keeper and rabbet alignment block attached to the same.

Figure 15 is a front view of a plain or one piece keeper.

Figure 16 is a side view of the same.

Figure 17 is a front elevation of a keeper with a removable alignment block but without removable silencer blocks.

Figure 18 is side elevation of the same.

Fig. 19, is a sectional view of Fig. 17, along lines A—A, B—B and C—C, respectively, the section along B—B showing the alignment block in place, the section along C—C being taken with the alignment block removed.

Figure 20 is a top plan view of Figure 15 and Figure 16.

Figure 21 is a front view of a keeper with one removable locking block and two resilient expanding members, the latter bringing the door in alignment with the pillar of the vehicle.

Figure 22 is a side elevation of the same.

Figure 23 is a front view of a keeper with two cut removable locking block but with two resilient expanding members.

Figure 24 is a side elevation of the same. Figure 25 is a section on line B—B and A—A, respectively, of Figure 23.

Figure 26, is a cross-sectional view of Fig. 21, on lines C—C, showing the locking block in place, and another section thereof showing the said block removed.

Referring to the drawings 1 indicates the pillar or post having its edge rabbeted at 13 and 2 is the keeper frame which consists of a plate having a longitudinal flange 2^a at one edge and transverse flanges 2^b at its ends and provided with transverse partitions 14. This arrangement provides end compartments 4, for the reception of the bolt receiving blocks 3 which are made of a suitable sound deadening material such, for example, as fibrous material, for the purpose of rendering the collision of the bolts with the blocks noiseless. These blocks are formed with tapered bolt receiving holes 6 and the blocks are beveled at 19 (see Figure 9) so that the bolt rides easily over the block in closing the door. The tapered socket 6 in each of the sound deadening blocks 3 has its mouth flaring outwardly as at 15 in Figure 2. In order to remove the sharp corner and enable the locking bolts to more quickly engage the socket. The removal of this sharp edge also reduces the wearing of the engaging bolt by avoiding any cutting of the same. The blocks 3 are held to the keeper frame by means of screws 7 and screws 8 also pass through the block 3, likewise the keeper frame and enter into the pillar 1 thereby tightening the block in the frame 30 and securing the frame to the pillar. In the central compartment 11 lying between the transverse partitions 14, is encased the alignment block 12 which is held to the keeper frame by means of screws 9 and screws 10 also passing through the alignment block 12, likewise the keeper frame and into the material of the pillar 1 thereby securing the parts to the pillar.

In Figure 7 the keeper frame 2 and removable block 3 are attached to the pillar 1. 19 represents the inclined sliding surface for the locking plungers.

In Figure 10 the pillar is shown with the space for the keeper frame cut away.

In Figure 11 a plain keeper frame without alignment block, as shown in Figures 15, 16, 21, 22 and 23 and 24 is attached to the pillar, therefore the rabbet line is missing.

In Figure 12 a keeper frame as shown in Figures 1, 2, 3 and 4 is attached to the pillar therefore the rabbet line 13 formed by the alignment block 12 is visible.

Figure 13 is a front view of a keeper as shown in Figures 15, 16, 21, 22, 23 and 24. 65 2 represents the rear line of the keeper. 6

the plunger engagement holes, 1 the pillar, 13 the rabbet line.

Figure 14 is a front view of a keeper frame as shown in Figures 1, 2, 3 and 4. 6 represents the taped holes in the removable blocks 70 3. 1 represents the pillar, 2 the keeper frame attached to the pillar. 12 indicates the removable alignment block shown in Figure 5 also in Figure 19.

As illustrated in Figure 13 with the style 75 of keeper frame used in said figure, the rabbet line 13 is missing for the entire length of the keeper frame.

In Figure 14 with the use of alignment block 12 which is furnished wide enough 80 and quickly removed from and attached again to the said frame. The rabbet line 13 can be quickly continued on the alignment block 12, and the disfigurement of the rabbet line 13 becomes less conspicuous in Figure 14 than in Figure 13.

In Figure 8 the alignment block 12 fills out the full space of the keeper frame opening.

In Figure 12 the same alignment block 12 90 is cut to correspond with the required rabbet line 13. This illustrates the unlimited adjustment of said alignment block to match rabbet line.

In Figure 9 in the front view of the removable locking block, 6 represents the tapered hole, 7 and 8 indicate holes to fasten it in the openings 4 in the frames shown in Figures 1, 2, 3, 4, 21 and 22. In Figure 9 in the sectional view 6 represents the tapered locking hole, 15 the removed edges, 19 the inclined sliding surface.

In Figures 15, 16, 17, 18, 19, 20, 23, 24 and 25 the 6 represents the tapered holes, 15 the removed edges, 19 the inclined sliding surfaces. If the tapered holes 6 or the surface lines 19 become worn in this style of keeper, the entire frame must be renewed. Whereas with the keepers shown in Figures 1, 2, 3, 4, 21 and 22 only the block 3 110 shown in Figure 9 needs renewal.

In Figures 21 and 22 16 represent openings for resilient expanding members 17, the latter extending over the edge of the keeper frame. This style keeper having only one 115 locking point, the expanding blocks 17 are forcing the door in alignment with the pillar. 18 represents tapered pins to hold 17 in the opening 16. 4 represents the opening for removable block 3 of Figure 9. Said block 3 is fastened to this keeper in the same method as described in Figures 1 and 2.

Figures 23 and 24 show a single locking keeper closely resembling the one of Figures 21 and 22. The only difference is that 125 the latter has the removable block 3 as shown in Figure 9, the former not.

While certain preferred embodiments of this device have been shown and described, it will be understood that changes of the 130

form, proportions, sizes and details thereof may be made without departing from the scope of the invention as defined by the appended claims.

5 Having described my invention, what I desire to secure by Letters Patent and claim is:

1. In a keeper of the class described, the combination of a housing, sound-reducing 10 removable bolt receiving members provided with bolt engaging sockets, a removable rabbit line alignment pad, and means for fastening said elements in the housing.

2. In a lock-keeper, a strike plate frame 15 provided with marginal flanges upon three of its edges and having transverse partitions extending across the plate from one of said flanges to provide a series of compartments, removable bolt receiving blocks provided 20 with sockets for receiving the bolts and mounted in alternate compartments.

3. In a lock-keeper, a strike plate frame formed with a block receiving compartment, a bolt receiving block provided with a bolt 25 receiving socket removably mounted in said compartment and having a beveled surface leading to said socket and over which the bolt slides to reach the socket.

4. In a lock keeper, a strike plate frame 30 provided with a removable block formed with a bolt receiving socket, the said block being made of sound deadening material, such for example as fibrous material.

5. A keeper of the class described, 35 consisting of a frame having encasing compartments, a sound-reducing interchangeable

plunger support and resilient expanding and contracting elements encased in said compartments, whereby a door can be brought in alignment with the adjacent pillar and remain in said position while said door remains locked.

6. In a keeper of the class described, the combination of a frame having a housing, 40 resilient expanding and contracting members arranged in said housing, and means to hold said members in said housing, said members being engaged and compressed by the door when closed.

7. In a lock keeper, a strike plate frame 50 provided with a series of compartments, bolt receiving blocks provided with sockets and mounted in alternate compartments, and an alignment block mounted in the compartment intermediate said bolt block compartments.

8. In a bolt keeper, a strike plate frame provided with block receiving compartments, an inwardly tapering recess formed in the bottom of each compartment, bolt receiving blocks provided with inwardly tapered bolt receiving sockets arranged in said compartments with the inner ends of said sockets registering with said recesses.

9. In a lock keeper, a strike plate frame 60 provided with block receiving compartments, blocks removably mounted in said compartments and provided with inwardly tapering bolt receiving sockets and said sockets having a flaring mouth at the outer 70 end thereof.

CARL MACK.
